Primary Examiner — Rachel A. Voorhies*Assistant Examiner* — Benjamin D. Wannemacher(74) *Attorney, Agent, or Firm* — Lerner, David, Littenberg, Krumholz & Mentlik, LLP(57) **CLAIM**

The ornamental design for an armorer tool, as shown and described.

DESCRIPTION

FIG. 1 is a front left perspective view of an armorer tool showing our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a front right perspective view thereof.

The broken lines of even length illustrate portions of the armorer tool that form no part of the claimed design. The broken lines of uneven length are boundary lines that form no part of the claimed design.
